ABSTRACT OF THE DISCLOSURE

A particulate sample is removed from a feed pipe carrying the sample by having a plurality of concentric pipes of varying diameters positioned within the feed pipe one above the other so that the sample in the feed pipe flows through successively decreasing diameters. The volume of the particulate sample is reduced while maintaining particle size distribution by placing a plurality of bars within the pipes to mix the sample. An extraction pipe of smaller diameter than the last concentric pipe and connected to the last concentric pipe leads to an external collection point where the particulate sample is removed.

The present invention is directed to a method of reducing the volume of a sample of fluidized particles while maintaining normal particle size distribution. Specifically the invention relates to the use of plural concentric pipes and bars placed within the pipes perpendicular to the flow of the solids.

In taking samples of crushed materials or other particulate matter (e.g., ores, oil bearing shale, catalysts, etc.) size segregation often occurs causing the sample to be non-representative. A non-representative sample will often result in incorrect analyses and cause errors in plant operations. The present invention avoids this problem by effectively remixing and redistributing the particles after each reduction in sample volume.

The apparatus of the present invention is particularly useful in oil shale retorting where particle size distribution is of particular significance. Fines in a retort feed, for example, cause a decrease in yield and bogging of the oil recovery system by being blown out of the retort with the product gases. It is possible for fines to cause retort operability problems such as uneven burning, and can even extinguish the flame in the combustion zone. Moreover large shale particles will not be efficiently retorted, and thus a loss in yields will occur. The retort conditions in oil shale processes can be varied to alleviate such problems, but this requires knowledge of the particle size distribution of the oil shale being fed the retort. The present invention provides such knowledge easily and inexpensively and thus provides for more efficient use of oil shale.

While the apparatus of this invention is particularly adapted for use in oil shale retort processes it may be employed in any instance where knowledge of particle size distribution of a particulate stream is desired.

Generally, the material to be sampled flows into a pipe and across a series of bars that prevent it from flowing in a straight line thus effectively mixing the sample. From this point, part of the sample passes inside a second, smaller, concentric pipe and is again mixed by more bars and passed on to a further, even smaller sample volume reducing pipe. Finally, the sample passes out of the main line and through a sample line which generally is smaller than the last sample reducing pipe. In general, since the material at the outer edges of the pipe may not be adequately mixed, the sample reducing pipes are made successively and gradually smaller as the sample passes through the system to insure that a true sample is

2

taken. Reductions of from about 2 or 5 to 50% in the cross-sectional area of the pipe can be generally used with the reduction in area between adjacent stages decreasing as the number of stages increases. The number of stages can vary and depends upon the volume of sample desired and the characteristics of the material to be sampled, although at least three stages are preferred.

Referring to the drawings, FIG. 1 is a section of the preferred embodiment of the invention showing the main line, the plural concentric pipes, the sample outlet pipe and the mixing bars.

FIG. 2 is a top view of the pipe showing the preferred method of attaching the concentric pipes to the inside of the main pipe.

FIG. 3 is a section of the preferred embodiment of the invention showing the main line, the plural concentric pipes, the sample outlet tube and the mixing bars opposed perpendicularly in adjacent mixing areas.

Specifically, the sample material enters the feed pipe at point 11 and passes over mixing bars 12 where the random particle distribution is assured. Part of the sample passes into concentric pipe 13 and the rest is rejected and flows down the area outside the smaller pipes.

The sample within concentric pipe 13 is remixed by another group of bars 12 and a portion of it passes on to the next concentric pipe 14 where it is again remixed, while the remainder passes out of the system through pipes 16 and 17.

As shown in FIG. 3, the mixing bars 12 in adjacent mixing areas may be opposed perpendicularly to each other.

The sample in concentric pipe 14 is further reduced in volume before entering and being remixed in concentric pipe 15, from which part of the sample passes into sample line 18 and can be collected for testing.

FIG. 2 shows the support for the top concentric pipe which is effected by plural braces 19 between the concentric pipe 13 and the feed pipe 17. There are three braces in the preferred embodiment but it is to be understood that any means that will support the concentric pipes and be sufficient to make the present invention operable will be acceptable.

To illustrate the invention, about 30,000 lbs. of oil shale were fed into a sampler, as the one shown in the drawing, over a four-day period with about 260 lbs. being taken out of the sample line during this period. The table compares (feed material and sample material) screen size required to pass a given percentage of the feed and sample materials, and shows a close correlation between the sample material and the feed material particle sizes.

TABLE

Percent of material passing	Screen size (inches)	
	Feed material	Sample material
80	0.090	0.098
60	0.052	0.060
40	0.030	0.040
20	0.011	0.013
10	0.005	0.005

It is claimed:

1. An apparatus for reducing the volume of a particulate sample while maintaining particle size distribution, said apparatus comprising a feed pipe carrying the sample, a plurality of concentric pipes of varying diameters, positioned within the feed pipe one above the others so that the sample in said feed pipe flows through successively decreasing diameter, concentrically arranged pipes, means for mixing the portion of said particulate sample passing through at least the first of the concentrically arranged pipes and sample extraction means arranged beneath the last of the concentrically arranged pipes for removing to an external collection point a portion of the particulate

sample which has the particle size distribution of the sample.

2. The apparatus of claim 1 wherein there are at least three concentrically arranged pipes.

3. The apparatus of claim 1 wherein there are mixing means in each of the concentrically arranged pipes.

4. The apparatus of claim 1 wherein the mixing means comprises a plurality of bars positioned within the first of said concentrically arranged pipes.

5. The apparatus of claim 6 wherein said bars are opposed perpendicularly in adjacent mixing areas.

6. The apparatus of claim 4 wherein there are mixing means in each of said concentrically arranged pipes.

7. The apparatus of claim 6 wherein there are at least three concentrically arranged pipes.

8. The apparatus of claim 1 wherein said extraction means is an extraction pipe forming a continuation of the last concentrically arranged pipe.

9. The apparatus of claim 8 wherein the extraction pipe is concentric with and smaller than said last concentrically arranged pipe.

10. The apparatus of claim 1 wherein each succeeding concentrically arranged pipe in the line of flow of the sample has from about 2 to 50% less cross-sectional area than the immediately preceding concentrically arranged pipe.
